UNITED STATES PATENT OFFICE.

WILBER J. PINE, OF KENOSHA, WISCONSIN.

WIRE FABRIC.

1,372,310.

Specification of Letters Patent. Patented Mar. 22, 1921.

Application filed July 23, 1917, Serial No. 182,269. Renewed October 11, 1920. Serial No. 416,296.

To all whom it may concern:

Be it known that I, WILBER J. PINE, a citizen of the United States, residing at Kenosha, county of Kenosha, and State of Wisconsin, have invented new and useful Improvements in Wire Fabrics, of which the following is a specification.

My present invention relates to new and useful improvements in wire fabrics of a resilient nature adapted for use in connection with spring mattresses, and more particularly of that type set forth in my co-pending application, Serial No. 182,269, filed July 23, 1917.

It is the object of this invention to provide a fabric composed of units of an exceedingly simple nature, connected to afford, as in my co-pending application, longitudinal lines of support affording maximum strength and permitting resilient yielding movements of the various units to properly distribute load stress throughout the fabric and thus avoid undesired general sagging.

A more detailed object is to provide a fabric of this nature wherein a plurality of connecting eye-loops are provided to afford a maximum resiliency in connection therewith.

With the above and other objects and advantages in view, the invention resides more particularly in the novel combination, formation and arrangement of parts herein-after described and pointed out in the appended claims.

In the drawings:

Figure 1 is a plan view of a section of wire fabric constructed in accordance with my invention.

Fig. 2 is a sectional view through the fabric on the line 2—2 of Fig. 1.

Referring now more particularly to the accompanying drawings, my improved fabric comprises a plurality of series of longitudinal units, the units of each series being mutually connected together and being connected by tie links with the units of adjacent series.

Each unit comprises a pair of wire shanks which are twisted together at one end to divide the shanks into pairs of relatively long and short sections, the corresponding shank sections being slightly divergent. The short shank sections are terminally bent to form eye loops 7 lying in a horizontal plane, and the longer sections

of the shanks are terminally bent to form eye-loops 8 lying in a vertical plane and interlocked with the eye-loops 7 of the next unit whereby a pair of direct longitudinal connections is afforded in each longitudinal series of units to provide a maximum strength particularly for heavy load conditions. The longitudinal series of units are transversely connected by the links 9 terminally bent to form eye-loops 10 interlocking with the horizontal eye-loops 7 of the shanks, to complete the fabric.

These tie links 9 correspond to the laterally connecting arms of the fabric units of my said co-pending application with respect to providing for a transverse resilient flexure of the shank sections to take up sag, but they do not afford the resilient opposition to relative longitudinal movement of transversely adjacent units in the manner afforded by said connecting arms, which are integral with their adjacent unit portions. The eyes 7, 8 and 10 are sufficiently large to permit relative sliding movement in curved lines, and by their size and number, a considerable general resilient yielding is procured under load conditions, in addition to the yielding procured by flexure of the shank portions.

I claim:

1. A wire fabric unit formed of a pair of longitudinally extending shanks twisted together intermediately of their ends, the ends of said shanks being at a substantial distance from the twisted portions, and free for transverse resilient flexure of the shank sections, and attaching means for adjacent units at the ends of said shanks.

2. A wire fabric formed of series of units each comprising a pair of separate shanks extending longitudinally of the fabric and twisted together intermediately of their ends, the ends of the unit, each comprising a pair of unconnected shank ends terminating in resilient attaching eyes interlocked with the shank eyes of longitudinally adjacent units, and transverse tie members having resilient eyes interlocked with the shank eyes.

3. A wire fabric unit formed of a pair of longitudinally extending shanks connected together at an intermediate point at a substantial distance from the ends of the unit, with the shanks extending from the point of connection along slightly divergent

110

lines, and each of said shanks terminating at each end of the unit in a resilient attaching eye.

4. A wire fabric unit comprising a pair
5 of longitudinally extending resilient shanks
twisted together adjacent one end of the
unit at a sufficient distance from both ends
of the unit to allow comparatively free lateral
separation, those portions of the shanks
10 between the said twist and the ends of the

units being relatively free and divergent,
and means for connecting the ends of the
shanks with adjacent side and end units.

In testimony whereof I affix my signature
in the presence of two witnesses.

WILBER J. PINE.
